Primary Examiner—Shanda C Hill*(74) Attorney, Agent, or Firm*—Banner & Witcoff, Ltd.(57) **CLAIM**

The ornamental design for a bottle, as shown and described.

DESCRIPTION

FIG. 1 is a top, front, right perspective view of a bottle showing a first embodiment of our new design;

FIG. 2 is a front view thereof;

FIG. 3 is a right side view thereof;

FIG. 4 is a rear view thereof;

FIG. 5 is a left side view thereof;

FIG. 6 is a top view thereof;

FIG. 7 is a bottom view thereof;

FIG. 8 is a top, front, right perspective view of a bottle showing a second embodiment of our new design;

FIG. 9 is a front view thereof;

FIG. 10 is a right side view thereof;

FIG. 11 is a rear view thereof;

FIG. 12 is a left side view thereof;

FIG. 13 is a top view thereof; and,

FIG. 14 is a bottom view thereof.

The broken lines shown in the drawing disclosure are for illustrative purposes only and form no part of the claimed design. The dash-dot lines which define the bounds of the claimed design form no part thereof.
